UNITED STATES PATENT OFFICE.

DAVID ADDISON JENKINS, OF KOKOMO, INDIANA, ASSIGNOR TO D. C. JENKINS GLASS COMPANY, OF KOKOMO, INDIANA, A CORPORATION.

REMOVABLE TOP FOR PITCHERS AND THE LIKE.

1,344,404.

Specification of Letters Patent. Patented June 22, 1920.

Application filed March 26, 1920. Serial No. 368,848.

To all whom it may concern:

Be it known that I, DAVID ADDISON JENKINS, a citizen of the United States, and a resident of Kokomo, county of Howard, and State of Indiana, have invented a certain new and useful Removable Top for Pitchers and the like; and I do hereby declare that the following is a full, clear, and exact description thereof, reference being had 10 to the accompanying drawings, in which like numerals refer to like parts.

This invention relates to liquid containers, such as pitchers and the like, and primarily to that class used in dispensing 15 syrups and other liquids, wherein the pitcher is provided with a hinged cover.

The chief feature of the invention is the provision of means for securing the cover to the pitcher so that the cover may be readily attached or detached for cleansing and 20 re-filling purposes.

A further feature of the invention is the positive locking and rigid construction of the cover connection between the cover and 25 pitcher.

The full nature of the invention will be understood from the accompanying drawings and the following description and claim.

30 In the drawings Figure 1 is a side elevational view of a pitcher embodying the invention. Fig. 2 is a front elevational view of the invention. Fig. 3 is an enlarged elevational view of a detail of the invention. 35 Fig. 4 is a longitudinal cross sectional view taken on line 4-4 of Fig. 3. Fig. 5 is a transverse sectional view taken on line 5-5 of Fig. 3. Fig. 6 is a side elevational view of a modified form of pitcher and cap, parts 40 being broken away to show some of the parts in detail. Fig. 7 is a similar view showing the detachable connection in another position.

In the drawings 10 indicates a syrup 45 pitcher or the like provided with the usual pouring spout 11, a handle 12, and a mouth portion 13. Said mouth portion 13 and spout 11 are suitably closed by the usual cover, such as a plate 14, shown in Figs. 1 50 and 2. Integral with said plate and extending rearwardly and upwardly therefrom is the usual finger piece 15.

Means for securing the cover plate 14 to the pitcher proper comprises a supporting 55 hinge member or plate 16 detachably se-

cured to said pitcher. Said supporting plate 16 is provided upon its upper portion with an angular portion 17, the same having at opposite sides upwardly and forwardly extending ears 18 adapted to be positioned within and adjacent corresponding depending and rearwardly projecting ears 19 formed integral with the finger piece 15, as shown in Figs. 1 and 2. A suitable hinge pin 20 secures the ears in operative position, and a suitable coiled spring 21 supplies tension to said hinge, so that the cover 14 will be returned to and maintained upon the mouth of the pitcher.

Means for detachably securing the supporting plate 16 to the pitcher 10 comprises a projecting boss 22, the same being elongated, and as shown in Figs. 1, 2 and 6, extends vertically and substantially in line with the handle. The projection 22, as 70 shown clearly in Fig. 5, has sidewardly projecting portions 23 forming a wedge. The plate 16 is provided with inwardly projecting side portions 24, said portions yieldingly engaging the wedge-shaped projections 23 of the elongated projecting boss 22. It will be noted that the supporting plate 75 may be slipped upon the projecting boss, as shown, and is thus detachably secured to the pitcher.

The means for locking the supporting plate 16 upon the pitcher comprises a circular projecting boss 25 formed upon and integral with the elongated boss 24, and preferably near the upper portion thereof. 80 The plate 16 is provided with a longitudinally extending slot 26 substantially parallel to the elongated projecting boss 22, and said slot terminates in a circular portion 27, the same being adapted to receive 85 the circular boss 25. When the supporting plate 16 is slid longitudinally of said elongated boss, the slot 26 encounters the circular projection 25 and the slotted ends of 90 said plate are separated to permit the circular projection to become seated in the circular slotted portion 27. When thus seated, the slotted ends of the plate 16 grip the elongated boss which forms a yielding engagement, and said circular slot and circular boss 95 positively lock the plate 16 to the pitcher.

In Fig. 6 a modified form of pitcher and cover connection is shown. The pitcher 100 100 is provided with the usual pouring spout 110

111, handle 112, pouring mouth 113, cap 114 and finger piece 115, as shown. In this instance the mouth 113 of the pitcher is provided with a channel 113^a which is adapted 5 to catch and receive any drippings or the like from the spout 111 and return the same to the interior of the pitcher in the usual manner. The cap also is provided with an engaging flange 114^a which is adapted to 10 be seated upon and engage the upper edge of the mouth 113. The supporting plate 116 is substantially similar to the plate 16 shown in Figs. 1 to 5 inclusive, having the longitudinal slot, circular slotted portion 15 and inwardly turned edges. Said plate 116 has a portion 117 turned back upon the plate 116, as shown in Fig. 6, said hinge forming portion 117 being provided with hinge forming ears 118. Adjacent said ears 20 118 are similar ears 119, the same being formed upon a hinge forming strip 123, said hinge forming strip being suitably secured to the finger piece 115, as by means of the inwardly turned flange portions 124. The hinge is also provided with the usual hinge 25 rod 120 and the spring 121.

The elongated boss 122, as shown in Fig. 7, extends substantially at right angles to the positions heretofore described. From the foregoing it will be understood that the elongated boss 122 may be formed upon the pitcher either adjacent the handle or upon the same and at substantially any angle required by the construction of the pitcher.

While the invention has been described 35 in great detail, it will be understood that the broader features thereof, particularly the detachable connection and the means for positively locking the connection, are not to be limited by the details of the de- 40 scription.

The invention claimed is:

A pitcher including a cover, an elongated boss positioned upon the pitcher, said boss being substantially wedge-shaped in cross 45 section, an elongated hinge supporting plate, including a body portion and having inwardly turned side edges, each adapted to engage the wedge-shaped side of said elongated boss, said plate being slidable longitudinally upon said elongated boss, hinge means supported near one end of said plate for pivotally supporting said cover, the body portion of said plate at the other end being slotted longitudinally intermediate 55 the side edges, said longitudinal slot terminating intermediate the ends of said plate body portion in an enlarged opening, and a boss projecting outwardly from said elongated boss and intermediate the sides thereof, said boss being complementarily formed so as to be seatable in said enlarged opening to yieldingly lock said plate to said pitcher.

In witness whereof, I have hereunto af- 65 fixed my signature.

DAVID ADDISON JENKINS.
